(57) **CLAIM**

The ornamental design for a tea cover, as shown and described.

DESCRIPTION

FIG. 1 is a perspective view of a tea cover showing my new design;

FIG. 2 is top plan view thereof;

FIG. 3 is a bottom plan view thereof;

FIG. 4 is a right side plan view thereof;

FIG. 5 is a left side plan view thereof;

FIG. 6 is a front elevational view thereof;

FIG. 7 is a cross-sectional view of the tea cover along 7-7 of FIG. 6; and,

FIG. 8 is a rear elevational view thereof.

The portions represented by broken lines form no part of the claimed design.
